DESIGN FOR A WHEEL

Carolus L. Eksergian and Talmon A. Davenport,
Detroit, Mich., assignors to Budd Wheel Com-
pany, Philadelphia, Pa., a corporation of Penn-
sylvania

Application September 16, 1933, Serial No. 49,270

Term of patent 14 years

To all whom it may concern:

Be it known that we, CAROLUS L. EKSERGIAN and TALMON A. DAVENPORT, citizens of the United States, residing at Detroit, in the county of Wayne and State of Michigan, have invented a new, original, and ornamental Design for a Wheel, of which the following is a specification, reference being had to the accompanying drawing, which forms a part hereof.

Figure 1 is a perspective view of our new design for a wheel.

Figure 2 is an axial profile view and

Figure 3 is a fragmentary elevational view.

Figure 4 is a sectional view taken through one of the spokes approximately on the line 4—4 of Fig. 2.

The wheel body portion of the design is its dominant feature, the hub cap and rim being relatively immaterial parts of the design.

We claim:

The ornamental design for a wheel, substantially as shown and described.

CAROLUS L. EKSERGIAN.
TALMON A. DAVENPORT.
